DESIGN FOR A PLASTIC CLOTHESPIN

John B. Tegarty, Buffalo, N. Y.

Application June 18, 1947, Serial No. 139,784

Term of patent 14 years

(Cl. D17—6)

To all whom it may concern:

Be it known that I, John B. Tegarty, a citizen of the United States, residing at Buffalo, county of Erie, and State of New York, have invented a new, original, and ornamental Design for a Plastic Clothespin, of which the following is a specification, reference being had to the accompanying drawing, forming a part thereof.

Fig. 1 is a perspective view of my clothespin;

Fig. 2 is a side elevation of the same;

Fig. 3 is a face view elevation taken at right angles to Fig. 2;

Fig. 4 is a transverse section taken on a plane indicated by the line 4—4 of Fig. 3, and

Fig. 5 is a transverse section taken on a plane indicated by the line 5—5 of Fig. 3.

I claim:

The ornamental design for a plastic clothespin, as shown.

JOHN B. TEGARTY.
